UNITED STATES PATENT OFFICE

ALBERT F. FIELD, OF ST. CATHARINES, ONTARIO, CANADA, ASSIGNOR TO THE AMERICAN FORK & HOE COMPANY, OF CLEVELAND, OHIO, A CORPORATION OF OHIO

RAIL ANCHOR

Application filed August 24, 1931. Serial No. 558,862.

My invention relates to rail anchors and relates more particularly to two-piece rail anchors, which, as is well known, commonly comprise two interlocked elements conjointly clamped onto a rail base, and one of which is engageable with a fixed portion of the railway road bed, such as a tie to restrain longitudinal creeping of the clamped rail relative to said tie or other fixed road bed part.

It has been previously proposed, as disclosed in the patent to Vaughan, No. 1,113,516, dated October 13, 1914, to provide a multi-piece rail anchor comprising a flattened bar made of spring steel extending beneath the rail and terminating in a hook for engaging a rail base flange, said bar having an upwardly extending portion on the other end thereof adjacent to the other side of the opposite rail base flange extending above the bottom of the rail, the upper end of the hook having a band extending laterally of the body of the bar, with a rigid shoe made of cast metal engaging the other rail base flange and having a jaw extending between the upturned end of the bar and the rail, said spring bar being sprung from a normal condition by twisting the same in applying it to the rail base, and the said shoe to force the said hook down on the top of the rail base in resiliently intending to resume its normal unstressed untwisted form.

Anchors of the above described Vaughan type have come into widespread use and have been very successful. However satisfactorily these anchors may have been in part, they have not fulfilled all requirements for a relatively inexpensive highly efficient means for preventing creeping of railroad rails and among the objections had to such Vaughan anchors are the following:

First, when cars of railroad trains traversing the rails become derailed, the relatively rigid unyielding cast shoes are engaged by the wheels of the derailed cars and the entire road bed is torn up and the damage to the cars and the road bed is very seriously increased over what would occur were such shoes not in place.

Second, the more practical commercial em-

bodiments of the Vaughan anchor have been expensive to manufacture and to maintain and are subject to considerable variation in manufacture, one from the other.

Third, the "bite" of the anchor on the rail base flanges achieved by the rigid shoes of such commercial form of anchors efficiently as is accomplished in other types of two-piece anchors, such for instance as the type exemplified by United States Letters Patent No. 1,682,370 to F. W. Cooper, dated August 28, 1928, which has also gone into widespread use, and which are not subject to the above said first objection nor to the above said second objection.

An object therefore of my invention is to provide an improved two-piece anchor which is not subject to the above said first objection.

Another object of my invention is to provide an improved two-piece anchor which is not subject to the above said second objection.

Another object of my invention is to provide an improved two-piece anchor which is not subject to the above said third objection.

Another object of my invention is to provide an improved two-piece anchor which is not subject to any of the above said enumerated objections.

Another object of my invention is to provide an anchor which is inexpensive to manufacture in quantities, and which will be highly efficient in use.

Another object of my invention is to provide an improved method of making a highly efficient rail anchor.

Another object of my invention is to provide an improved rail anchor made at least in part of a rolled section of steel.

Other objects of my invention and the invention itself will become apparent to those skilled in the art to which my invention appertains from the following description of an embodiment of my invention and in which description reference will be had to the accompanying drawings illustrating said embodiment, wherein:

Fig. 1 is a perspective view of a rail anchor

embodying the principles of my invention, said anchor being illustrated as consisting of two parts shown in assembled relation, no showing of a railroad rail associated therewith being illustrated;

Fig. 2 is a plan view of the embodiment of Fig. 1, shown applied to a fragment of a railroad rail base;

Fig. 3 is a side elevational view of a yoke element employed in the embodiments of Figs. 1 and 2;

Fig. 4 is a rear elevational view of a clamp element of the foregoing embodiment;

Fig. 5 is a side elevational view of the apparatus of the foregoing figures shown as applied to a railroad base fragment shown in transverse section, a fragment of a railroad tie shown in operative relation therewith;

Fig. 6 is a plan view of a second embodiment of my invention;

Fig. 7 is a side elevational view of the said second embodiment shown as applied to a railroad rail base, shown in transverse section, a portion of the yoke element of said embodiment of a railroad tie associated therewith; a fragment being shown as broken away to expose an otherwise hidden part of the clamp element;

Fig. 8 is a plan view of the apparatus of Fig. 6;

Fig. 9 is an end elevational view of Fig. 7, except that in dotted lines thereon an end of the yoke element is indicated approaching its ultimate position in place shown in solid lines;

Fig. 10 is a plan view of the clamp element of the said second embodiment; and

Fig. 11 is a perspective view thereof taken from above said clamp element.

Referring now to Figs. 1 to 5 inclusive of the drawings, the first embodiment of my invention, which is illustrated therein, comprises preferably a yoke element substantially as shown in the said prior patent to Vaughan, No. 1,113,516, in combination with a novel form of clamp element made substantially entirely of sheet steel material having a considerable spring quality, said steel being generally termed "spring steel", and I will herein use the term "spring steel" in its most generally accepted sense as distinguished from steel castings and the like, which are relatively unyielding.

The clamp element of my invention comprises a blank of sheet metal of preferably uniform thickness bent to provide a flanged clamping piece having a main body portion 1, a pair of substantially parallel forwardly extending clamping flanges 2 and 3, and a lateral extension 4 having a relatively short clamping flange 5 which extends forwardly in spaced parallel relation to the flange 3 and therefore the flange 2.

The flange 2 is disposed in a vertical plane, and is provided with a lower portion 2a of

considerable area whereby to provide on its outer surface a tie engaging face whose area will be sufficient to minimize undue wear of the engaged surface of the railroad tie 6, shown in Fig. 2. The flange 2 is provided with a notch 7 extending inwardly of its upward portion from its most forward edge 12, the notch comprising a substantially horizontal edge portion 7a and an upwardly extending divergent edge portion 7b which edge portions are joined posteriorly by an upwardly extending rounded portion 7c. The purpose of relatively forming the said edge portions as described is to provide jaws 10 and 11 of suitable form to snugly fit onto a lateral flange of a rail base, such as the flange 8 of the rail base 9, shown in Fig. 2.

However, I consider it important to make the notched edge surfaces 7a and 7b somewhat less slightly divergent than the engaged surface of the rail base flange 8, whereby resiliently maintained contact will always be had between the more forward edge portions 7a and 7b and the engaged portions of the rail base flange, the clamping jaws 10 and 11 provided by the notches due to the inherent resiliency of the steel material of the clamp being adapted to resiliently spread sufficiently to permit the driving of the jaws onto said rail base flange. When so positioned on the flange 8, the secondary jaw element formed by the clamping flange 5 overlies the rail base flange 8 while the intermediately disposed jaw formed by the upper edge of the flange 3 underlies the rail base 8 in engagement with its bottom surface.

When thus positioned on the rail base flange, the clamp element 1 engages said flange at three longitudinally spaced portions of said flange, first by the jaws of the flange 2, second by the jaw of the underlying flange 3 and third by the jaw of the overlying flange 5. This arrangement practically provides two sets of jaws for the clamp element, the first being the slightly resiliently yieldable set of jaws 10-11, and the second being the upper jaws 5 and 10 in combination with the lower jaw 3. Both sets of jaws are effective simultaneously to prevent movement of the clamp on the rail flange longitudinally thereof, and are efficiently maintained in position because of the resilient qualities inherent in the clamp material whereby when the clamp is "driven on" the rail base flange 8 there will be a resilient yielding of the parts thereof, and the resulting reaction will tend to hold the clamp in position throughout the period of use of the anchor.

The application and removal of the anchor from the rail base will be readily understood, being accomplished in a manner similar to that described in the aforesaid patent to Vaughan, and will be well understood from the disclosure of said patent and a brief de-

scription, only, thereof will be incorporated herein; it is to be noted, however, that the Vaughan patent discloses an anchor employing a third locking element in addition to the clamp element and yoke element; the locking element is preferably omitted in the anchor of my present invention, although in its broader phases the invention is applicable to anchors employing such a locking element although the embodiment herein illustrated and described is merely a two-piece rail anchor and employing no separable third locking element.

In applying the rail anchor to the rail base flanges 8, the clamp 1 is first applied to one side of the rail base in the position shown in Fig. 1, the hook 13 then being hooked over the other side of the rail base and the yoke 14 carrying said hook is brought into such a position, whereby the said hooked end of the yoke supports one end thereof by engagement with the upper side of the rail base and the other end of the yoke is brought into a position whereby it rests upon the projection 15 provided on the clamp element near the bottom of the back portion 4 thereof; a tool is then employed to grasp the upstanding arm 16 of the yoke and to rotate it in such a manner that the intermediate portion 14 of the yoke is slightly twisted until the inner edge of the upstanding arm 16 snaps over the upper projection 17 of the clamp, whereupon the lateral surface of the arm 16 engaging the edge 18 of the projection 17 will prevent the yoke from regaining its normal unstressed form, whereupon the yoke, by virtue of the arm 16 will hold the clamp 1 by its back 4 closely against the edge of the adjacent rail base flange 8 and will maintain the resiliently spread jaw elements 3, 5, 10-11 in clamping engagement with the rail base flange.

Removal of the anchor from the rail is accomplished by giving the arm 16 a slight rotational movement to displace the lower end 16' from vertical alignment with the lowermost projection 15 of the clamp, whereupon the arm 16 may be driven downwardly past said projection to detach the yoke element 14 from the clamp and rail base.

Having now described a preferred embodiment of my invention, a brief description only of a second embodiment thereof will be required. The second embodiment of my invention is illustrated in Figs. 6 to 11 inclusive, it being understood that the yoke element, as illustrated in Fig. 8, is also preferably employed in the said second embodiment.

The clamp thereof is substantially the same in form and operation as the previously described clamp illustrated in Fig. 4, except that the clamp of Figs. 10 and 11 is cut from a rolled length of resilient steel material of substantially T or I-section in sub-

stantially a manner like that described in my co-pending application, Serial No. 558,861, filed Aug. 24, 1931 (docket 1063). In its finished form, it is substantially like the clamp shown in Fig. 4 for the said first embodiment, except that an additional flange 19 disposed preferably in the plane of the notched flange 2' is provided and is effective to provide additional area, adapted to engage the railroad tie 7, against which it abuts. The flanges 3' and 5' and the projections 15' and 17' find their counterpart in form and functional characteristics in the said first embodiment and will not require additional description.

The provision of the flange 19 also stiffens the clamp to cause it to resist distortion to a greater extent than the clamp of the first embodiment. However, the clamp of Figs. 10 and 11 is sufficiently resilient as to possess to a high degree the advantages previously ascribed to the inherent resiliency of the clamp element. The operation of assembling the anchor on to a rail base and disassembling it therefrom is performed in the same way as that described for the foregoing embodiment.

Having thus described my invention in certain embodiments, I am aware that numerous and extensive departures may be made from the embodiments illustrated and described, but without departing from the spirit of my invention.

I claim:

1. An anchor of the Vaughan two-piece type comprising a yoke and a clamp, said clamp being of resilient sheet metal and comprising a back plate portion and three approximately parallel relatively spaced vertical flanges extending from the same side of the said back portion, said flanges providing alternately disposed upper, lower and upper jaws, respectively adapted to clamp a rail base flange and resiliently held thereon by said yoke.

2. In a rail anchor of the Vaughan two-piece type in combination with the torsional resilient yoke thereof, of an inherently resilient clamp formed of sheet metal comprising a back plate and three flanges extending from the same side of said back plate in spaced relation, a first of said flanges providing a pair of superposed resilient jaws adapted to embrace the upper and lower surfaces of a rail base flange, the other of said flanges providing respectively lower and upper jaws which are longitudinally spaced from each other longitudinally of the rail base, the lower flange being spaced longitudinally of the rail base from said first flange, said jaws adapted to be resiliently clamped and maintained on the rail base flange by engaging upper and lower surfaces thereof being retained thereon by said yoke.

3. In a rail anchor in combination with a

yoke terminating at one end in an upstanding inturned hook adapted to embrace a rail base flange and the other end in an upstanding clamp retaining arm, of a substantially resilient clamp element adapted to be maintained on the other rail base flange by said arm comprising a resilient sheet metal stamping having a back plate portion engageable by said yoke arm and a plurality of substantially parallel flanges adapted to grip the upper and lower surfaces of the associated rail base flange and to be slightly resiliently distorted from normal form by the spreading effect of said flange.

4. In a rail anchor in combination with a yoke terminating at one end in an upstanding inturned hook adapted to embrace a rail base flange and the other end in an upstanding clamp retaining arm, of a substantially resilient clamp element adapted to be maintained on the other rail base flange by said arm comprising a resilient sheet metal stamping having a back plate portion engageable by said yoke arm and a plurality of substantially parallel flanges adapted to grip the upper and lower surfaces of the associated rail base flange and to be slightly resiliently distorted from normal form by the spreading effect of said flange, an outer one of said flanges comprising a pair of superposed jaws and an intermediate of said flanges forming a jaw engaging said rail base flange at a side opposite to the flange side engaged by two other of said jaws.

5. An anchor of the Vaughan two-piece type comprising a yoke and a clamp, said clamp being of resilient sheet metal and comprising a back plate portion and three approximately parallel relatively spaced vertical flanges extending from the same side of the said back portion, said flanges providing alternately disposed upper, lower and upper jaws, respectively adapted to clamp a rail base flange and resiliently held thereon by said yoke, said clamp back portion comprising also a locking projection extending rearwardly from its upper portion over which an angular projection of said yoke may be torsionally snapped and resiliently maintained in pressed distorted form thereby.

6. An anchor of the Vaughan two-piece type comprising a yoke and a clamp, said clamp being of resilient sheet metal and comprising a back plate portion and three approximately parallel relatively spaced vertical flanges extending from the same side of the said back portion, said flanges providing alternately disposed upper, lower and upper jaws, respectively adapted to clamp a rail base flange and resiliently held thereon by said yoke, said yoke being formed of a strip of spring sheet steel terminating at one end in a hook adapted to embrace a rail base flange and at the other end in an upstanding angular projection, the back portion of said

clamp being provided with a rearwardly extending projection disposed between said lower and said last-named upper jaw and above the plane of said lower jaw, said yoke angular projection adapted to be snapped over said projection of said back when said strip is torsionally twisted against the power of its inherent resiliency and is retained thereby in distorted form to effect an anchoring bite by said flange-embracing hook upon the embraced rail base flange.

7. In a rail anchor of the Vaughan two-piece type in combination with the torsional resilient yoke thereof, of an inherently resilient clamp formed of sheet metal comprising a back plate and three flanges extending from the same side of said back plate in spaced relation, a first of said flanges providing a pair of superposed resilient jaws adapted to embrace the upper and lower surfaces of a rail base flange, the other of said flanges providing respectively lower and upper jaws which are longitudinally spaced from each other longitudinally of the rail base, the lower flange being spaced longitudinally of the rail base from said first flange, said jaws adapted to be resiliently clamped and maintained on the rail base flange by engaging upper and lower surfaces thereof being retained thereon by said yoke, and a projection extending rearwardly from said back plate adapted to retain said yoke in operative engagement with said clamp back plate.

8. In a rail anchor in combination with a yoke terminating at one end in an upstanding inturned hook adapted to embrace a rail base flange and the other end in an upstanding clamp retaining arm, of a substantially resilient clamp element adapted to be maintained on the other rail base flange by said arm comprising a resilient sheet metal stamping having a back plate portion engageable by said yoke arm and a plurality of substantially parallel flanges adapted to grip the upper and lower surfaces of the associated rail base flange and to be slightly resiliently distorted from normal form by the spreading effect of said flange, said yoke being formed of resilient steel material, said back plate portion comprising a rearwardly extending projection, said yoke being torsionally retained between an intermediate one of said parallel flanges and said back projection.

In testimony whereof I hereunto affix my signature this 25th day of July, 1931.

ALBERT F. FIFIEND.
